UNITED STATES PATENT OFFICE.

CHARLES HIRSCH, OF BUFFALO, NEW YORK, ASSIGNOR TO W. A. CASE & SON MANUFACTURING COMPANY, OF BUFFALO, NEW YORK.

CONVERTIBLE STOP-COCK.

SPECIFICATION forming part of Letters Patent No. 731,684, dated June 23, 1903.

Application filed February 18, 1903. Serial No. 143,904. (No model.)

To all whom it may concern:

Be it known that I, CHARLES HIRSCH, a citizen of the United States, residing at Buffalo, in the county of Erie and State of New York, have invented new and useful Improvements in Convertible Stop-Cocks, of which the following is a specification.

This invention has more particular reference to stop-cocks which are capable of use either as a right-hand or a left-hand cock, as circumstances may require.

The principal object of my invention is the construction of a stop-cock of this character which can also be converted into an ordinary cock in which the plug turns all the way around.

A further object is to so construct the stop-cock that while having this three-fold capacity the wear of the rotary plug and its seat can be readily taken up.

In the accompanying drawings, consisting of two sheets, Figure 1 is a sectional elevation of a stop-cock embodying my invention. Fig. 2 is a bottom plan view of the cock, the plug and its washer and clamping-nut being omitted. Fig. 3 is a cross-section in line 3 3, Fig. 1, the ball being omitted. Fig. 4 is a detached view of that side of the washer containing the circular ball-channel. Fig. 5 is a fragmentary longitudinal section of the lower portion of the cock, showing the washer reversed to form an ordinary cock without stops. Fig. 6 is a sectional elevation of the cock, showing a modified construction of the improvement. Fig. 7 is a bottom plan view of the body of said cock. Fig. 8 is a cross-section in line 8 8, Fig. 6, the ball being omitted.

Similar letters of reference indicate corresponding parts throughout the several views.

A indicates the body or casing of the cock, and B the tapering plug, arranged in a corresponding seat in the casing and having the customary waterway b.

b' is the usual reduced screw-stem at the small end of the plug to which the clamping-nut C is applied, and D is a washer, secured to the stem between this nut and the adjacent lower portion a of the casing. In the preferred construction shown in the drawings this washer is compelled to turn with

the plug by making the portion of the plug-stem above its screw-thread square or of other flat-sided and symmetrical form, as shown at b², and providing the washer with 55 a corresponding opening.

In the construction shown in Figs. 1 to 5 the flat lower end of the casing A is provided with a cavity e, adapted to receive the upper portion of a ball F or similar loose member, 60 and the washer D is provided in one side with a pair of segmental grooves or channels d d', which are arranged concentrically with the plug, and one or the other of which is adapted to register with the cavity e and receive 65 the lower portion of said ball. The ball thus forms a projection which extends into the segmental channel opposite the cavity e, and the ends of said channel form stops or shoulders which strike the ball upon 70 turning the plug in one or the other direction, thereby limiting the movement of the plug. Each of the channels d d' is of the proper length to restrict the movement of the plug to about a quarter-turn and the two 75 channels are located on opposite sides of the plug, so that by adjusting the washer on the plug to bring one or the other of its channels in the proper position with reference to the ball F a right-hand or a left-hand stop-cock 80 is obtained accordingly. Figs. 1 and 3 show the cock in the form of a right-hand stop-cock. In order to convert it into a left-hand cock, the screw-nut C and the washer D are removed from the plug, the latter is given a 85 half-turn in its seat, and the washer is replaced after having been turned a quarter in the direction of the arrow in Fig. 3.

On the side opposite that containing the segmental channels d d' the washer is preferably provided with a circular channel d², arranged concentrically with the plug and having the same radius as the channels d d', so as to receive the ball F when the washer is reversed to the position shown in Fig. 2. 90 As the washer presents no stop-shoulders in this reversed position, the plug can be turned through a complete circle in either direction, like that of an ordinary cock without stops. When the cock is converted into this form, 100 the circular channel of the washer in conjunction with the cavity e of the casing serves

- as a pocket for the ball F, preventing loss of the ball and keeping it ready at hand for converting the cock into a right or a left hand stop-cock, as desired. By this construction 5 the same cock can be readily converted into any one of the three types in common use, thus obviating the necessity of manufacturing and keeping in stock three separate kinds of cocks.
- 10 While I prefer to employ a loose ball for forming a stop projection on the casing, the latter may be provided with a teat or fixed projection instead of a ball.
- If desired, the arrangement of the ball-cavity 15 e and the segmental washer-channels d d' may be reversed, as illustrated in Figs. 6, 7, and 8—that is, the ball-cavity may be formed in one side of the washer, as shown at e', and the channels in the lower end of the casing, 20 as shown at d'.

In each of the constructions herein shown and described the stop device is arranged between the casing and the washer mounted on the tapering plug. The same cannot, therefore, 25 cut the plug or form a bur thereon, which would cause leakage, and it does not interfere with the tightening of the plug when the same becomes loose from wear, thereby permitting wear of the plug to be taken up, 30 as in ordinary stop-cocks of this class.

I claim as my invention—

1. The combination of a casing having a seat, a rotary plug arranged in said seat, a reversible washer secured to the projecting 35 lower end of the plug, one of the opposing faces of the casing and the washer being provided with a cavity and the other with a segmental channel arranged to register with said cavity, and the washer being provided in its 40 opposite face with a circular channel of the

same radius as said segmental channel, and a loose member arranged in said cavity and adapted to project either into said segmental channel or into said circular channel, substantially as set forth.

2. The combination of a casing having a seat, with a member projecting from the lower end of the casing on one side of said seat, a plug arranged in said seat, and a washer reversibly secured to said plug and provided on 50 opposite sides with a segmental channel and a circular channel, respectively, said channels being both of the same radius and adapted to interchangeably receive the said member, whereby the cock may be converted into 55 a stop-cock or an ordinary cock, at will, by reversing the washer on the plug, substantially as set forth.

3. The combination of a casing having a tapering seat and provided at its lower end 60 on one side of said seat with a cavity, a tapering plug arranged in said seat and provided at its small end with a screw-stem and above said stem with a square portion, a washer reversibly applied to said square portion and provided in one side with opposing segmental channels arranged concentrically with the plug and in its opposite side with a circular channel of the same radius as said segmental channels, and a ball arranged in 70 said cavity and adapted to coöperate with either of said channels, substantially as set forth.

Witness my hand this 14th day of February, 1903.

CHARLES HIRSCH.
